CLAIM

The ornamental design for a metal bottle as shown and described.

DESCRIPTION

FIG. 1 is a front perspective view of the metal bottle;

FIG. 2 is a front elevation view thereof;

FIG. 3 is a top plan view thereof;

FIG. 4 is a bottom plan view thereof;

FIG. 5 is a front perspective view of a metal bottle according to an alternative embodiment;

FIG. 6 is a front elevation view of the metal bottle of FIG. 5;

FIG. 7 is a top plan view of the metal bottle of FIG. 5;

FIG. 8 is a bottom plan view of the metal bottle of FIG. 5;

FIG. 9 is a front perspective view of a metal bottle according to an alternative embodiment;

FIG. 10 is a front elevation view of the embodiment of FIG. 9;

FIG. 11 is a top plan view of the embodiment of FIG. 9;

FIG. 12 is a bottom plan view of the embodiment of FIG. 9;

FIG. 13 is a front perspective view of a metal bottle according to an alternative embodiment;

FIG. 14 is a front elevation view of the embodiment of FIG. 13;

FIG. 15 is a top plan view of the embodiment of FIG. 13;

and,

FIG. 16 is a bottom plan view of the embodiment of FIG. 13.

The broken lines in the drawings illustrate the portions of the metal bottle that form no part of the claim.
